UNITED STATES PATENT OFFICE.

WILLIAM LE ROY EMMET, OF EAST ROCKAWAY, NEW YORK.

INSULATOR.

SPECIFICATION forming part of Letters Patent No. 443,174, dated December 23, 1890.

Application filed September 18, 1890. Serial No. 365,399. (No model.)

To all whom it may concern:

Be it known that I, WILLIAM LE ROY EMMET, a citizen of the United States, residing at East Rockaway, Queens county, and State 5 of New York, have invented or discovered a certain new and useful Improved Insulator, of which improvement the following is a specification.

In the accompanying drawings, which make 10 part of this specification, Figure 1 shows a transverse section of the spindle and insulator on the line where said insulator is gripped by the yoke and span-wire, with a plan of said yoke and span-wire. Fig. 2 is a side elevation of Fig. 1, looking at the insulator along 15 the line of span-wire; Fig. 3, a central section through Fig. 2 on a vertical plane at right angles with the direction of the trolley-wire; and Fig. 4, a side view on the side of 20 the span-wire loop, showing yoke and span-wire secured around an insulator with button-spindle.

One purpose of my invention, generally 25 stated, is to devise simple and strong forms of insulators from which the weight of the wires may be supported by strains of compression instead of tensile strains, which prevents rupture and grips the insulator more strongly as the weight increases.

30 A further object is to fasten the insulator to the upper wire by connections exterior to the body of said insulator, which method of connection leaves the dome of said insulator with an unbroken water-shed. The connections are also designed to be easily applied, removed, and exchanged.

35 The improvements herein described show methods of suspending and insulating any wire from another, but are peculiarly applicable to electric-railway work, and the upper and lower wires are therefore referred to as span and trolley wires.

The clip shown in the several views is not 40 herein claimed, as it, *inter alia*, constitutes the subject-matter of another application, of even date herewith, filed by me, Serial No. 365,928.

In Figs. 1 to 3, 1 is an insulator, preferably 45 of wood, dome-shaped at the top, and with a groove 2 running around its surface on a line about half-way from its top to the base. The base of said insulator 1 is best concave to 50 guard against moisture, and the insulator is

centrally and longitudinally cored to receive a connecting-spindle, the upper part of which is threaded at 3, supported by nut 5, resting 55 upon a shoulder 6. The plug 7 closes the opening of the core. The connecting-spindle just below the body has a shoulder 8 and is extended downward into two forks 9 9, which inclose a lug 10 on a clip 11, supporting trolley-wire 12. Rivet 13 fastens forks 9 9 to lug 10. Said insulator 1 is fastened to span-wire 14 by a yoke 15, of malleable iron, hooked at both ends, said hooks grasping 60 said span-wire on either side of said insulator and said span-wire being deflected from a straight line to lie in the groove 2 and partially embrace said insulator.

In Fig. 4, 16 shows any insulating mass of material molded or cast around a connecting-spindle 17.

Other connecting devices than hooks may be used on the yoke 15, and the extent of contact of said yoke or said span-wire with said insulator may be greatly varied.

The contour of the surface of the insulator may be changed so as to be conical, channeled, &c.

The method of securing the insulator to the span-wire may be employed on other forms 80 of insulators than those shown, and the insulators shown may be used with other methods of attachment to span and trolley wires than here exhibited.

I claim—

1. The combination of a deflected span-wire, a yoke secured at both ends to said span-wire at or near said points of deflection, an insulator inclosed between said span-wire and said yoke, and a trolley-wire suspended 90 from said insulator and by its weight causing the insulator to be firmly gripped between said span-wire and said yoke, substantially as set forth.

2. The combination of a yoke secured at 95 each end to a span-wire, a span-wire between the points of said connection deflected from the straight line, a body of insulating material gripped between said yoke and said span-wire, a connecting-spindle sustained in said 100 insulating material by a nut on said spindle resting upon a shoulder of said insulating material, said spindle having a shoulder immediately below said insulating material, de-

vinces for connecting said spindle with a trolley-wire, and said trolley-wire, substantially as set forth.

3. The combination of a yoke secured at each end to a span-wire, a span-wire between the points of said connection deflected from a straight line, a body of insulating material gripped between said yoke and said span-wire, a metallic fixture partially incased by said insulating material, devices for securing said metallic fixture to a trolley-wire, and said trolley-wire, substantially as set forth.
4. An insulator consisting of a body of in-

sulating material, a connecting-spindle sustained in said body by a nut resting on a shoulder formed in said body, said spindle having a shoulder immediately below said body, and devices for connecting said spindle to a trolley-wire, substantially as set forth.

In testimony whereof I have hereunto set my hand.

WILLIAM LE ROY EMMET.
